MECHANISM FOR LIMITING THE CALLING POSSIBILITIES OF A TELEPHONE APPARATUS

Fritz Marti, La Chaux-de-Fonds, Switzerland

Application August 18, 1937, Serial No. 159,790
In Switzerland August 19, 1936

4 Claims. (Cl. 179—90)

The invention relates to an exchange system for a telephone with limited calling possibilities, in which impulse transmission takes place on the return movement of the impulse-dial. To said dial a shaft is coupled, adapted to rotate two control disks on which concentric partition walls are arranged, whereby the walls of one of said disks have gaps corresponding to the blocked up numerals. Furthermore a spring-controlled 10 feeler, adapted to penetrate into said gaps, is provided, which feeler, at the end of its operation, closes a contact which, in its turn, is capable of bridging the impulse-contact.

Other objects and features of the invention 15 will be apparent as the following description proceeds, reference being had to the accompanying drawings, in which

Fig. 1 is the wiring diagram of the two embodiments illustrated as example.

Fig. 2 is a perspective, schematic representation of the first embodiment.

Fig. 3 is a partial and schematic representation of the second embodiment.

In Fig. 1 the principal parts of a telephone station according to the invention are shown. T indicates the receiver, Mi the microphone, Tr the transformer, D the impulse dial, C₁ the switch controlled by said dial, F the hook switch which closes the circuit when the receiver is taken off. 25 With the aid of the terminals a and b the telephone station is connected to the line and thus to the local exchange. The bell S of the station is connected in series with a condenser C which prevents the passage of direct current but lets 30 through the alternating current supplied by the exchange for operating the bell.

As may be seen from Fig. 2 dial D is provided with ten digit holes distributed over the circumference of the dial and numbered in a known 40 manner. This well-known disk is fastened to a shaft 11 carrying a ratchet wheel 12 and is under the influence of a release-spring 13. A worm wheel 15 is loosely placed on shaft 11 and meshes with worm 16 coupled with a centrifugal governor 17 the rotating masses of which are represented schematically and denoted by 18. A pawl 22 mounted on worm wheel 15, and acted upon by spring 23, glides over the teeth of the ratchet wheel, when dial D is turned in the direction of arrow 10, but drives worm wheel 15 and, thereby, governor 17, when the dial returns in the direction of arrow 11 under the effect of spring 13 which is initially stressed. Worm wheel 15 carries a cam disk 19 with bosses 20 distributed on its circumference in the same way as

the digit holes on the impulse dial. These bosses act on a contact 21 of switch C₁ opening the circuit shown in Fig. 1. Referring to this Figure 1 it will be understood that switches C₂, C₃, C₄ . . . connected in parallel with switch C₁ short-circuit the latter, if any of these contacts is closed and thus permit the transmission of predetermined numbers only, if said switches are closed for all other numbers which one may attempt to set. 5

In Fig. 1, a lock S₂ is illustrated as a means of 10 closing one of these switches, viz: C₄, if it is desired to prevent any use of the telephone station.

There is also a relay R connected in series with switches C₂ to C₄. This relay serves the purpose 15 either to give notice that the apparatus cannot be used, or, in case of a prepayment telephone station, to return the money.

A wheel 14 is fixed to shaft 11, alternately rotating either in the direction of arrow 10 or of 20 arrow 11. This wheel 14 carries a pawl 28 pivoted at 29 and pressed against stop 31 by means of spring 30. Wheel 14 serves as a connecting means between the impulse dial and the mechanism according to the invention. In the embodiments shown this mechanism is located at the subscriber's station, but it might also be provided at the local exchange or elsewhere, whereby it would have to be electro-magnetically coupled with the impulse dial. 25

The mechanism comprises two parallel shafts 33 and 25. Shaft 33 carries ratchet wheel 32 which, at the beginning of every forward motion of the impulse dial, always rotates said shaft in the same direction by means of pawl 28. Dial D is operated in a well-known manner by introducing a finger into the desired hole and by rotating it until the finger touches stop 32. Then the dial is let go whereupon it runs back under the effect of spring 13. These two inverse movements of the dial are transmitted to shaft 25 by means of gear wheel 24 fixed to said shaft and meshing with wheel 14. 30

Shaft 33 is under the influence of spiral spring 34 whose tension increases at every step of ratchet wheel 32. This latter wheel is held up by pawl 38 which, in its turn, is mounted on shaft 56 and acted upon by spring 57, which latter presses pawl 38 against ratchet wheel 32. Pin 36 attached to ratchet wheel 32 bears against flexible 40 stop 31 when wheel 32 is in its initial position. 45

The mechanism shown comprises only one group of two members which serve the purpose of selecting between the permitted and non-permitted subscriber-numbers, viz: in cases where 50 55

the use of the station must be limited for any reason, be it that a subscriber wants to prevent third parties from setting up trunk connections, or that the station is a prepayment station for local calls or for special trunk calls. Since trunk connections are set up by using code numbers prefixed to the subscriber's individual number and in order to prevent fraudulent use of the station, it will suffice to prevent the transmission of a certain digit at a certain place of the subscriber's number.

The selecting members are formed by disks 35, 27 fixed to shafts 33 and 25 respectively. Each of them carries, on one of its faces, concentric cylindrical partition walls equidistant from each other by a space which allows a feeler to pass between these walls. For disk 35 this feeler is a roller 42 and for disk 27 a roller 41. The axis of these rollers are parallel to shafts 33 and 25 and parallel to shaft 49 of lever 39 carrying said rollers. This lever is controlled by a spring 43 fixed to the frame and tending to apply said rollers to the disks. One arm of said lever is provided with a toothed segment 46. Arm 48 pivoted to pin 59 and controlled by spring 54 keeps said lever in the represented position by means of tooth 47 against the effect of spring 43. The pitch of segment 46 is chosen in such a way, as to correspond with the displacement of the rollers from one to another of said partition walls. These walls each possess at least one gap through which the rollers may pass. In disk 35 the gaps of the partition walls are located in such a way that the gap of the outermost wall, after disk 35 has been rotated one step, lies in juxtaposition to roller 42; after disk 35 has been moved a further step, the gap of the second wall lies in juxtaposition to roller 42, etc. In disk 35 as many partition walls could be provided as there are digits in the subscriber's number, however, in the embodiment illustrated the selection is limited to the three first digits. The innermost wall is formed as a solid cylinder. The ends of the other partition walls of disk 35 are bent inwards in order to form a ramp from one wall to another for roller 42.

One gap of each partition wall of disk 27 is arranged on radius 09. When impulse dial D and disk 27 are in their initial position, 50 roller 41 is also in line with radius 09 as is shown in Fig. 2. The position of the other gaps depends on the subscriber-numbers to be permitted or non-permitted. In the example of Fig. 2 the transmission of the numbers 354 to 55 359 is excluded. To this end the outermost partition wall of disk 27 is provided with a gap on radius 3, which corresponds to the position of digit hole 3 on impulse dial D; the second partition wall has a gap on radius 5 corresponding to digit hole 5 and the third partition wall has a gap extending over the space from radius 4 to 9.

Behind disk 27 and on shaft 25 disk 26 is provided comprising notches distributed over the circumference according to the position of the digit holes of impulse dial D. An arm 51 is fixed to shaft 56 of arm 48. Tongue 52 is linked to arm 51 in order to be adapted to swing about a steady position controlled by spring 53. In said steady position the tongue enters far enough into a cut-out of disc 26, so that, when it has been inclined at the commencement of rotation of disk 26 in the direction of arrow 70 marked on wheel 24 and when it has penetrated into a notch at the end of this rotation, it cannot as-

sume an inverse inclination on the return motion of disk 26 without repelling arm 51. The arrangement is such that this operation takes less time than disk 26 requires to turn one step. Finally lever 39 comprises an arm 44 by which it can operate key 45 of switch C₃.

Be it supposed that number 354 should be rung up. The first movement bringing digit 3 of dial D to stop 72 advances ratchet wheel 32 with the help of pawl 28 by one tooth and pawl 38 keeps the ratchet wheel in this new position, in which roller 42 is in line with radius 1 of disk 35. At the same time gap 3 of disk 27 is in juxtaposition to roller 41 and notches 1 and 2 of disk 26 have passed tongue 52 which now engages notch 3. Dial D is now released and runs back, tongue 52 is reversed, arm 43 releases segment 46, whereupon roller 42 drops upon the second partition wall and roller 41, through the gap on radius 3, falls into the first partition of disk 27 and that before disk 27 has had time to go back too far. Arm 44 has thus approached key 45 by about a third of the amount required for closing the circuit at C₃. Thus it follows that the three interruptions of the circuit produced by bosses 20 at C₁ in this same return movement, have been transmitted to the local exchange. Lever 39 is now kept in position with the aid of the second tooth of segment 46 and disk 27 is again in its initial position with roller 41 in line with radius 09, but in the first partition of disk 27. Then digit 5 is dialled. Workings similar to those previously described now occur but with the difference that roller 42 drops upon the third partition wall and roller 41 passes through the gap on radius 5.

Though roller 41 is now between the second and the third partition wall switch C₃ does not yet close the circuit and the interruptions caused by dialling digit 5 are also transmitted. When, 40 finally, digit 4 is dialled for the purpose of completing the transmission of number 354, roller 42 is in line with radius 3 of disk 35, and the third tooth of segment 46 released by tooth 47. The third partition wall of disk 27 has a gap on radius 4, so that the rollers can enter the third partitions of the selecting disks and apply to the innermost walls, i. e., to the solid cylinders. Now that lever 39 has carried out its maximum motion, arm 44 closes the circuit at C₃. At the 50 moment when this closing is effected, disk 27 has still to carry out almost the whole return motion, because it has, up to said moment, only run back as far as the distance required to operate the tongue. Bosses 20 of disk 19 have, 55 therefore, not yet operated impulse contact C₁ by which the subscriber's number should be transmitted, so that, since the circuit is closed at C₃, the interruptions at C₁ when they finally occur during further return motion of dial D into its initial position, are without any effect. Owing to the fact that one gap of the third partition wall of disk 27 extends over the space of radii 4 to 9, not only the transmission of number 354, but also of numbers 355 to 359 will be 60 excluded in the same way as above described.

Lever 39 must now be returned to its initial position shown in Fig. 2. To this end the mechanism comprises a shaft 66 to which are attached: a member 65 for hanging up the receiver, a finger 69 adapted to co-operate with lever 48 and a finger 68 co-operating with pawl 38. Receiver hook 65 can be moved between two stops and spring 67 tends to press said hook against the upper stop.

It may be seen that when the receiver is hung upon hook 65 tooth 47 disengages segment 46 at the same time as pawl 38 disengages ratchet wheel 32. Spring 34 then drives shaft 33 and disk 35 into their initial position, thereby forcing roller 42 to ascend the ramps of disk 35 and to move lever 39 back into its initial position. During this return motion roller 41 passes through the gaps on radius 60 of disk 27. Roller 42 now rests on the exterior partition wall. Tooth 47 will engage segment 46 as soon as the receiver is taken off for a new call.

From the above it results that the digits, when selected exclude the transmission of a number in dependence on the place, which they occupy in the subscriber-number. Therefore a fraud consisting in falsifying this place would render the mechanism ineffective.

Indeed a person acquainted with the selecting workings might transmit number 35 by operating dial D in the following manner: digit hole 8 is brought to stop 72, then moved backward three steps only, then stopped for a certain period and finally released so that it causes five interruptions when returning into initial position. When dialling in this way tongue 52 would be operated but once, so that digit 5 would be transmitted, without roller 41 dropping into gap 5 of the second partition wall.

Switch C₂ serves to prevent such a fraud.

This switch is closed when the whole mechanism is in the initial position shown in Fig. 2. When moving dial D pawl 38 is turned, whereby contact spring 59 is lifted by finger 55. This contact spring is formed so as to be kept in this raised position by means of tooth 60 of lever 62 which is pivoted at 63 and pressed against the free end of the shaft of worm 16 by means of spring 64. Contact spring 59 is provided with a lateral notch the width of which is equal to the total of the width of lever 62 entering the notch and the height of tooth 60. On the opposite side of tooth 60 lever 62 carries a second tooth 61 of the same height as the first. Both teeth are ratchet-shaped. When contact spring 59 rises, it displaces tooth 60, lever 62, after that, returns under the effect of spring 64, whereby contact spring 59 is supported by the horizontal flank of tooth 60. At this moment governor 17 is still at rest, for it rotates only at the return motion of the impulse dial. As soon as this return motion begins, wheel 15 tends to displace worm 16 in the direction of arrow 73. The axial play of worm 16 is large enough to repel lever 62. Tooth 60 then disengages contact spring 59 which now drops upon tooth 61 where it is held without closing the circuit. If, for a fraudulent purpose, the dial is stopped during its return motion the axial thrust on the worm ceases, since ratchet wheel 12 no longer drives wheel 15 by means of pawl 22. The inertness of the rotating masses 18 of the governor cause an ulterior rotation of worm 16, whereby the stopped wheel 15 acts as a stationary nut, so that the worm is displaced to the left. Spring 64 then moves lever 62 in an anticlockwise direction whereby tooth 61 disengages contact spring 59 which, in its turn, closes switch C₂. The second digit is thus not transmitted to the local exchange.

The mechanism shown in Fig. 3 only differs from that of Fig. 2 by the provision of two feeler-levers for each group of disks 35 and 27, instead of only one, whereby the station, instead of excluding the aforesaid numbers, will only transmit these latter.

Lever 39a differs from lever 39 by the fact that it only carries roller 41, roller 42 is placed on a second lever 74, loosely arranged on shaft 40 of lever 39a. This second lever does not cooperate with lever 48. Thus its spring 79 constantly 5 presses roller 42 to disk 35. The position of lever 39a, does, as in Fig. 2, not depend on the position of disk 35 until its toothed segment has been released. From this moment its motion is limited by a pin 75 mounted on lever 74. This latter 10 carries a shaft 71 to which lever 78 is pivoted. This latter raises key 45 when lever 74 lifts shaft 77. Furthermore lever 78 turns in the same direction as lever 39a when the latter is released.

Number 354 will be transmitted in the following manner: After the first rotation of dial D roller 42 is in line with radius 1 of disk 35 and by the effect of spring 79 applied to the second partition wall. Lever 78 closes switch C₃. This latter remains closed as long as roller 41 after 20 the release of lever 39a does not meet a gap of disk 27. However, roller 41 passes through the gap on radius 3, so that lever 39a touches pin 75. The left end of lever 78 is lowered by this motion of lever 39a and, thereby, the circuit is again 25 opened at C₃ and the interruptions at C₁ are transmitted. The same workings occur when dialling the digits 5 and 4, whereby roller 41 passes on radius 5 through a gap of the second partition wall and on radius 4 through a gap of 30 the third partition wall. Therefore, numbers 354 to 359 which were excluded in Fig. 2, are, in this embodiment, the only transmissible numbers. If the first digit is not a 3, roller 41 cannot pass through the first partition wall and the circuit 35 remains closed at C₃, while, on the contrary, it remains open in Fig. 2.

Instead of a single group of selecting disks and feeler-levers and a switch C₃, the mechanism might comprise several groups with various possibilities of use. In prepayment stations, for instance, one group will transmit numbers which are free from charge. Each of the other groups will only transmit those subscriber-numbers for which the same charge is to be paid. To this 45 end in a coin box means must be provided for electrically connecting the several contacts C₃ with one another.

In case the mechanism limiting the calling possibilities is separated from the telephone station 50 the talking line itself may serve the purpose of connecting said mechanism with said station, whereby a device must be provided producing such impulses in said line, that shafts 33 and 25 carry out the same motions as they would do 55 if they were driven by the mechanical means illustrated in the drawings.

I claim:

1. In an exchange system for a telephone with limited calling possibilities an impulse-dial, a 60 shaft coupled to said impulse-dial, an impulse-contact adapted to be controlled on the return movement of the dial, two control disks rotated by said shaft, concentric partition walls arranged on said disks, the walls of one of said disks having gaps corresponding to the blocked up numerals, a spring controlled feeler adapted to penetrate into said gaps, a contact adapted to bridge said impulse-contact and to be closed at the end of the feeler operation in order to render ineffective any 65 further operating of the impulse-dial.

2. In an exchange system according to claim 1, wherein one of the control disks is arranged to be rotated by the impulse-dial during the complete return movement of the latter, and the 70 75

other control disk is arranged to be rotated one step at each series of impulses of said impulse contact.

3. In an exchange system according to claim 1, wherein the first of said control disks is arranged to be rotated by the impulse-dial during the complete return-movement of the latter and the second disk is arranged to be rotated one step at each series of impulses, a toothed segment integral with said feeler and a spring-controlled arm carrying a stop adapted to co-operate temporarily with said segment to permit the feeler to come into contact with the second control disk.
4. In an exchange system according to claim 1, wherein the first of said control disks is arranged to be rotated by the impulse-dial during

the complete return movement of the latter and the second disk is arranged to be rotated one step at each series of impulses, a toothed segment integral with said feeler and a spring-controlled arm carrying a stop adapted to co-operate temporarily with said segment to permit the feeler to come into contact with the second control disk and a notched disk provided with a gap and integrally connected to the first control-disk and a spring controlled pivoted tongue mounted on the axis of said stop-carrying arm and arranged to cooperate with said notched disk to render said stop-arrangement temporarily ineffective.

FRITZ MARTI. 15
